UNITED STATES PATENT OFFICE.

WILLIAM H. CRANE, OF POUGHKEEPSIE, NEW YORK, ASSIGNOR TO MOLINE PLOW COMPANY, A CORPORATION OF ILLINOIS.

HARVESTER-ELEVATOR.

1,232,229.

Specification of Letters Patent.

Patented July 3, 1917.

Application filed July 31, 1916. Serial No. 112,210.

To all whom it may concern:

Be it known that I, WILLIAM H. CRANE, a citizen of the United States, residing at Poughkeepsie, in the county of Dutchess and State of New York, have invented certain new and useful Improvements in Harvester Elevators, of which the following is a specification, reference being had therein to the accompanying drawing.

10 This invention relates to the grain carrier or elevator mechanism of harvesters, which receives the grain from the platform conveyer and elevates it to the binding mechanism, such elevator mechanism comprising usually a lower inclined grain carrier in the form of an endless carrier apron passing at its ends around upper and lower carrier rolls mounted in a lower elevator frame, and an upper carrier apron passing around upper and lower carrier rolls mounted respectively in the upper and lower ends of an upper elevator frame, the grain from the platform conveyer being delivered between the lower ends of the two carrier 25 aprons and being elevated thereby and discharged at their upper ends to the binder deck.

My invention is directed particularly to the support for the lower carrier roll of the upper carrier apron, to enable the roll to be moved to and from the upper carrier roll in order to regulate the tension of the apron, and to enable the lower carrier roll to move away from the lower grain carrier in order 30 to prevent the lodgment or clogging of the grain between the lower ends of the two carrier aprons.

In accordance with my invention the lower carrier roll for the upper apron is journaled in supporting arms of improved form and construction, mounted in an improved manner on the upper elevator frame so as to swing back and forth relatively thereto to and from the lower grain carrier, the arms 45 being capable also of an endwise movement relatively to the frame, which movements are controlled and actuated by a suitable actuating device mounted in the frame and engaging the arms.

50 In the accompanying drawings:

Figure 1 is an elevation of the lower portion of the upper carrier apron, the latter being broken away to expose the elevator frame, the lower carrier roll, and the arms 55 in which said roll is journaled.

Fig. 2 is a vertical sectional elevation on an enlarged scale taken on the line 2—2 of Fig. 1, showing the relative position of the lower grain carrier and the platform conveyer, the carrier roll supporting-arms 60 being shown in their lower position to maintain tension on the apron.

Fig. 3 is a similar view with the lower grain carrier and platform conveyer omitted, the supporting arms being shown 65 in their upper position to relieve the carrier apron of tension.

Fig. 4 is a sectional elevation on the line 4—4 of Fig. 5 showing the spring actuated member for urging the movable carrier roll 70 toward the lower grain carrier.

Fig. 5 is a sectional elevation on the line 5—5 of Fig. 2.

Fig. 6 is an edge view of the upper elevator frame with its upper and lower carrier rolls and the carrier apron supported 75 thereby.

Referring to the drawings:

1 indicates the lower portion of the lower grain carrier consisting of an endless carrier apron 2 passing at its lower end around a lower carrier roll 3 and at its upper end around an upper carrier roll (not shown) the said rolls being mounted as usual in the lower elevator frame (not shown); and 4 indicates the platform conveyer by which the grain is conveyed to the elevator mechanism.

5 indicates the upper elevator frame consisting as usual of the two end bars 5^a, which frame is supported in the customary manner from the main frame of the harvester, in inclined position over the lower carrier apron. An upper carrier roll 6 is journaled between the upper ends of the end bars, and 95 a lower carrier roll 7 is journaled in sustaining arms 8, 8 mounted on the inner sides of the end bars near their lower ends as shown in Fig. 1, an endless carrier-belt 9 passing around said rolls so as to coöperate 100 with the lower carrier apron 2 in elevating the grain delivered between the two aprons by the platform conveyer.

In accordance with my invention the arms 8 are in the form of plates provided each 105 with an upper slot 10 and a lower slot 11 extending longitudinally of the arm, the upper ends of the arms being extended laterally inward in the form of lips 12, the upper surfaces of which are flat for the purpose 110

presently to be described. These arms are mounted on the respective end bars 5^a in such manner that they may swing transversely to and from the lower grain carrier, and may also move endwise relatively to the frame. To effect this mounting of the arms, pivot bolts 13 are applied to the end bars 5^a and are extended through the upper slots in the arms, the effect of which is to 5 pivotally connect the arms between their ends with the elevator frame, while permitting said arms to move endwise relatively thereto. At their lower ends the arms are formed with bearing openings in which 10 journals 14 on the opposite ends of the roll 7 are loosely mounted, so that in the endwise and pivotal motions of the arms the carrier roll 7 will be moved respectively to and from the upper carrier roll 6 and will 15 move also to and from the lower grain carrier in the manner to be more fully described hereinafter. Extending in the lower slots 20 11 of the arms are studs 15 having fixed to their outer ends sockets 16 which sockets 25 extend in housings 17 fixed to the end bars 5^a and formed with opposing guiding walls 18 extending transversely of the end bars, between which walls the stud 15 is guided. 30 Spiral springs 19 are seated in the guiding 35 housings, one end of the springs bearing against the sockets 16 on the studs, and the other ends bearing against the ends of the housings, the said springs tending to hold the studs in the opposite ends of the housings, maintaining the arms 8 and consequently the carrier roll 7 yieldingly in operative relation to the lower grain carrier to properly coöperate with the same in elevating the grain.

40 It will be understood from the foregoing construction that the lower carrier roll 7 is held yieldingly by the springs 19 so as to maintain the lower portion of the carrier apron in proper relation to the lower grain carrier, so that in the event of the clogging 45 of the grain entering between the upper and lower aprons, the lower portion of the upper carrier apron may yield and move away from the lower apron to permit the grain 50 to pass without interruption in the conveying operation.

The endwise movements of the arms to move the roll 7 to and from the upper roll 6 in order to control the tension of the apron 55 is controlled by an actuating member in the form of a rock shaft 20 mounted in the end bars 5^a above the upper ends of the arms as shown in Fig. 1. The ends of the shaft are formed with journals 21 and 22 mounted 60 in suitable bearing openings 23 in the end bars, and between these journals the shaft is formed with a crank portion 24 which is adapted when the shaft is rocked in its bearings to engage the upper flat surfaces 12 on the arms, the journal 22 being extended out-

wardly beyond the end bar and being provided on its end with a handle 25 for rocking the shaft. When the rock shaft is in the position shown in Figs. 1, 2 and 5, the crank 24 will be projected downwardly and 70 engaging the lips on the upper ends of the arms the latter will be held in their lower positions with the roll 7 sustained so as to maintain the apron 9 under tension. When now the rock shaft is turned a half revolution, the crank will be swung around to its upper position as shown in Fig. 3, which 75 action will release the arms and will relieve the tension on the apron.

In the use of this mechanism to properly 80 tension the apron when the latter has become loose on the carrier rolls, the handle 25 is turned from its upper position as shown in Figs. 1, 2 and 5 downwardly to the dotted line position indicated in Fig. 3, 85 by which action the crank will be disengaged from the ends of the arms and the latter will then be free to move upwardly endwise as shown in Fig. 3. In this position 90 of the parts, the slack in the belt may be taken up, usually by means of buckles on the ends, whereupon the handle 25 being turned back again to its former position the crank will act on the upper ends of the arms and shift the same endwise to their lower 95 position, thereby moving the carrier roll 7 downwardly away from the upper carrier roll and placing the apron under tension. The handle of the rock shaft is releasably 100 locked in position by suitable means, in the present instance by a spring actuated latch 105 26 mounted to move endwise in the end bar of the frame and provided on its outer end with a hook to embrace the handle.

From the construction described it will be 110 understood that when the rock shaft is in position to hold the arms in their lower position, the arms will be free to swing on their pivotal axes, the flat surfaces 12 on the upper ends of the arms sliding beneath and 115 in engagement with the crank as the arms swing on their axes.

It will be observed that in my construction, the sustaining arms carrying the carrier roll 7 are pivotally mounted between 115 their ends on the elevator frame and that the arms are wholly disconnected from the actuating member 20, the crank portion of the actuating member bearing against the flat surfaces 12 on the upper ends of the arms. 120 This permits the arms to move freely on their axes without interference by the actuating member, in which movements the upper ends of the arms will move relatively to the crank portion of the actuating member, being thereby subject to the holding action of the crank in maintaining the belt under proper tension, while permitting the lower end of the apron supported on the carrier roll to move to and from the lower carrier. 125

In the foregoing description and accompanying drawings I have disclosed my invention in the particular detailed form which I prefer to adopt, but it will be manifest that these details may be variously changed and modified without departing from the limits of the invention; and it will be understood that the invention is not limited to any particular form or construction 10 of the parts except in so far as such limitations are specified in the claims.

Having thus described my invention, what I claim is:

1. In a harvester, the combination of a 15 lower grain carrier, an upper elevator frame, an upper carrier roll mounted in said frame, arms pivotally mounted between their ends on the frame and movable endwise in relation thereto, a lower carrier roll journaled 20 in said arms below their pivotal axes, an endless carrier apron supported by said rolls, and an actuating member mounted in the frame and adapted to engage the arms and move them endwise to carry the lower 25 roll away from the upper roll, said arms being disconnected from the actuating member to enable them to rock on their axes to permit the lower roll to move to and from the lower grain carrier.

30 2. In a harvester, the combination of a lower grain carrier, an upper elevator frame, an upper carrier roll mounted in said frame, a lower carrier roll also mounted in the frame and movable bodily to and from the 35 lower grain carrier and also to and from the upper carrier roll, an actuating member to control said last mentioned movement of the lower roll, a spring sustained by the frame and acting to urge said lower carrier 40 roll toward the lower grain carrier, and an endless carrier apron passing around said rolls.

3. In a harvester, the combination of a 45 lower grain carrier, an upper elevator frame, an upper carrier roll mounted in said frame, arms pivotally mounted between their ends on the said frame and movable endwise relatively to the same, a lower carrier roll journaled in said arms below their pivotal axes, 50 an endless carrier apron supported by said rolls, said arms being provided above their pivotal axes with flat surfaces, and an actuating member mounted in the frame and engaging said flat surfaces to move the arms endwise to force the lower carrier roll away 55 from the upper carrier roll, the said flat surfaces being movable relatively to the actuating member in the pivotal motions of

the arms to permit the lower carrier roll to move to and from the lower grain carrier. 60

4. In a harvester, the combination of a lower grain carrier, an upper elevator frame, an upper carrier roll mounted in the elevator frame, arms pivotally mounted in the frame to move to and from the lower grain carrier, the said arms being movable also endwise relatively to the frame, a lower carrier roll journaled in said arms, an endless carrier apron supported by said rolls, spring actuated members sustained by the frame 70 and engaging said arms to urge them toward the lower grain carrier, and an actuating member sustained by the frame and engaging the arms to move them endwise.

5. In a harvester, the combination of a 75 lower grain carrier, an upper elevator frame, an upper carrier roll mounted in said frame, arms pivotally mounted in said frame to move to and from the lower grain carrier, said arms being movable also endwise relatively to the frame and being provided with longitudinal slots, a lower carrier roll journaled in said arms, an endless carrier apron supported by said rolls, studs mounted on the said frame and movable transversely 80 relatively thereto and engaging in the slots in the arms, springs sustained by the said frame and bearing on the studs to urge the arms toward the lower grain carrier, and an actuating member sustained by the frame 85 and engaging said arms to move the same endwise.

6. In a harvester, the combination of a lower grain carrier, an upper elevator frame, an upper carrier roll mounted in said frame, 95 two arms provided each with upper and lower slots extending longitudinally thereof, fixed pivot bolts sustained by the frame and extending in the upper slots, whereby the arms are pivotally sustained and movable 100 endwise relatively to the frame, spring actuated studs mounted on the frame and movable transversely thereof and extending in the lower slots in the arms, a lower carrier roll journaled in the arms, an endless 105 carrier apron supported by said rolls, and an actuating member mounted on the frame and engaging the arms to move the same endwise.

In testimony whereof, I have affixed my 110 signature in presence of two witnesses.

WILLIAM H. CRANE.
